A. W. MELANDER.

FILTER FOR SANITARY FAUCET DRINKING FOUNTAINS.

APPLICATION FILED DEC. 20, 1915.

1,260,233.

Patented Mar. 19, 1918.

UNITED STATES PATENT OFFICE.

AUGUST W. MELANDER, OF SAN FRANCISCO, CALIFORNIA, ASSIGNOR, BY DIRECT AND MESNE ASSIGNMENTS, TO FOUNTAIN FAUCET COMPANY, A CORPORATION OF MINNESOTA.

FILTER FOR SANITARY FAUCET DRINKING-FOUNTAINS.

1,260,233.

Specification of Letters Patent. Patented Mar. 19, 1918.

Application filed December 20, 1915. Serial No. 67,774.

To all whom it may concern:

Be it known that I, AUGUST W. MELANDER, a subject of the King of Sweden, residing at San Francisco, in the county of 5 San Francisco and State of California, have invented new and useful Improvements in Filters for Sanitary Faucet Drinking-Fountains, of which the following is a specification.

10 My invention relates to improvements in faucet drinking fountains, and the objects of the invention are to provide means, in such a fountain, for filtering the water rising therefrom which can be easily removed 15 for the purpose of cleaning or changing the same; also means for directing a stream of water so that it will impinge upon the filtering means uniformly and without tending to damage the same; also means for regulating 20 said distributing means; also means for preventing the entrance of impurities into the drinking fountain.

In the accompanying drawing, the figure is a sectional view of my improved sanitary 25 faucet drinking fountain.

Referring to the drawing, 1 indicates a faucet drinking fountain containing a conduit 2 leading to a downwardly directed spout 3 and a conduit 4 leading to an upwardly directed nozzle 5. Said nozzle is threaded on the outer side and screwed thereon is the lower portion 6 of the casing of a drinking fountain. A set screw 7 is employed to secure said lower portion upon 30 said nozzle in the most desirable position dependent upon the pressure under which the water is forced through the nozzle, as will be hereinafter explained. Upon said lower portion is screwed, as shown at 8, 35 the upper portion of the casing of said fountain, which is preferably hemispherical for convenience in drinking, and is formed at its upper central portion with a cylindrical vertical tubular inward extension 9. Said tubular extension is formed with a 40 shoulder 10, against which is placed a circular piece 11 of fine wire mesh, held in position by a short tube 12, driven tightly into said tubular extension. Said upper portion is formed with an inwardly extending annular flange 13, between which and the upper circular edge of the lower portion are interposed a circular 45

disk 14 of filtering material, preferably a suitable fabric, and also, above the disk 14, 55 a disk 15 of perforated sheet metal, said disks being held in position by screwing down the upper portion of the casing upon the lower.

Formed integral with, and extending 60 across, the lower portion, is a spider or cross-shaped piece 16, the central part of which is immediately above the center of the slightly conical upper end of the nozzle. The object of this arrangement is to prevent 65 the water impinging only at the center of the filtering material, and therefore, since it emerges from the nozzle under great pressure, causing it to rapidly disintegrate. By its presence immediately over the outlet nozzle, 70 said cross-piece forces the water through the openings 17 thereof, so that it is distributed with practical uniformity against the whole lower surface of the filtering material, and consequently the wear of 75 the filtering material is very small. Notwithstanding that the pressure at each point of the under side of the filtering material is greatly diminished as compared with pressure at the nozzle, and therefore the 80 pressure on the upper side thereof is also diminished, it results that, since the water emerges through a hole having an area much smaller than that of the filtering material and disk, the pressure of the fountain is 85 considerable.

The casing of the drinking fountain can be raised or lowered upon the nozzle to increase or decrease the distance between the nozzle and the cross-piece as may be 90 found best to distribute the water flowing through the openings in the cross-piece, and, when so raised, it may be secured in that position by the set screw.

Any object falling on the wire screen will 95 immediately be driven out by the rush of water therethrough, when the fountain is turned on.

In accordance with the patent statutes, I have described the principles of operation 100 of my invention, together with the apparatus which I now consider to represent the best embodiment thereof, but I desire to have it understood that the construction shown is only illustrative, and that the invention can be carried out by other means 105

and applied to uses other than those above set forth within the scope of the following claims.

Having described my invention, what I claim as new and desire to protect by Letters Patent is:—

1. A drinking fountain comprising, in combination, a lower portion adjustably secured about the nozzle of a water-feed pipe, said lower portion being externally screw-threaded at its upper extremity and having a spider provided with a deflecting portion disposed above the nozzle, an upper portion having an integral centrally depending tube forming an outlet and being screw threaded at its lower end for securance to the upper extremity of the lower portion, said upper portion having an inwardly extending annular flange disposed in a plane removed from the lower end of the tube, and a circular disk of filtering material interposed and secured between the upper end of said lower portion and said flange.
2. A drinking fountain comprising, in combination, a lower portion adjustably secured about the nozzle of a water-feed pipe, said lower portion being externally screw-threaded at its upper extremity and having a spider provided with a deflecting portion disposed above the nozzle, an upper portion having an integral centrally depending tube forming an outlet and being screw threaded at its lower end for securance to the upper extremity of the lower portion, said upper

portion having an inwardly extending annular flange disposed in a plane removed from the lower end of the tube, a disk of filtering material supported upon the upper end of said lower portion, and a perforated sheet metal disk disposed upon and covering said filtering disk, said disks being locked in position by said annular flange.

3. A drinking fountain comprising, in combination, a lower portion adjustably secured about the nozzle of a water-feed pipe, an upper portion removably secured to the upper extremity of said lower portion and having a spider and an integral depending tube forming an outlet in substantial alinement with said nozzle and spider, an inwardly extending annular flange projecting from said upper portion in a plane below the lower end of the tube, a disk of filtering material interposed and secured between the upper end of said lower portion and said flange, said tube being provided with an annular inner shoulder, a circular screen resting against said shoulder, and a tubular insert forced into the lower end of said tube for holding said screen in position against the shoulder.

In testimony whereof I have hereunto set my hand in the presence of two subscribing witnesses.

AUGUST W. MELANDER.
